(57) **CLAIM**

The ornamental design for a "stringed musical instrument string height gauge," as shown and described.

DESCRIPTION

FIG. 1 is a right front perspective view of a stringed musical instrument string height gauge showing my new design; FIG. 2 is right rear perspective view thereof; FIG. 3 is a left side elevation view thereof; FIG. 4 is a right side elevation view thereof; FIG. 5 is front elevation view thereof; FIG. 6 is a rear elevation view thereof; FIG. 7 is a top plan view thereof; FIG. 8 is a bottom plan view thereof; and, FIG. 9 is a perspective view, showing my new design in a state of use.

In FIGS. 1-9, the broken lines represent the portions of the design that form no part of the claim. In FIG. 9, the broken lines depicting a portion of a string instrument and a portion of a hand, illustrate the design as used and form no part of the claim.
